(57) **CLAIM**

The ornamental design for embroidery machine, as shown and described.

DESCRIPTION

FIG. 1 is a front view of an embroidery machine;

FIG. 2 is a top view thereof;

FIG. 3 is a right-side view thereof;

FIG. 4 is a rear view thereof;

FIG. 5 is a bottom view thereof; and,

FIG. 6 is a perspective view thereof.

The left-side view contains no ornamentality and is omitted.

The broken lines are for illustrative purposes only and form no part of the claimed design.
